WRENCH HEAD

Louis F. Marcanello, 526 W. Fisher Ave.,
Philadelphia, Pa. 19120

Filed July 28, 1972, Ser. No. 276,048

Term of patent 14 years

Int. Cl. D8—05

U.S. Cl. D8—17

FIG.1.

FIG.2.

FIG.3.

FIG.4.

FIG. 1 is a plan view of a wrench head embodying my new design;

FIG. 2 is a side elevation of the wrench head;

FIG. 3 is an end elevation of the wrench head; and

FIG. 4 is a plan view on a reduced scale showing the wrench head of my invention mounted on a torque wrench handle, which is shown in broken lines for illustrative purposes only.

I claim:

The ornamental design for a wrench head, substantially as shown and described.
